UNITED STATES PATENT OFFICE.

HARRY G. WEBSTER, OF CHICAGO, ILLINOIS.

AUTOMATIC TELEPHONE-SWITCH.

1,390,409.

Specification of Letters Patent. Patented Sept. 13, 1921.

Application filed April 19, 1916. Serial No. 92,080.

To all whom it may concern:

Be it known that I, HARRY G. WEBSTER, a citizen of the United States, residing at Chicago, in the county of Cook and State 5 of Illinois, have invented a certain new and useful Improvement in Automatic Telephone-Switches, of which the following is a full, clear, concise, and exact description, reference being had to the accompanying 10 drawings, forming a part of this specification.

My invention relates to automatic switches such as are employed in telephone systems for extending connections from one line or 15 trunk to another line or trunk.

The switch which I shall describe has been illustrated in connection with a call-distributing telephone system for which use it is particularly adapted. But it is to be 20 understood that the principles of the invention are applicable to switches employed for other purposes. It is also to be understood that while the particular controlling circuit, in connection with which I have illustrated the switch, contain points of novelty, some of which are hereinafter claimed, 25 that render the particular system especially useful in connection with the switch, I do not intend to limit the switch to use in connection with those particular circuits 30 whether used for the above, or other analogous purposes.

The switch which I have illustrated is a rotary uni-planar stepping switch, forming 35 an improvement upon the specific type of switch shown and described in the patent to Sidney Hand Browne, No. 1,073,589, granted September 23, 1913. The novel features pointed out in the appended claims 40 are, however, applicable to other types of switches.

It has been customary heretofore to provide a stepping ratchet and a holding pawl which pawl is controlled by a release 45 magnet.

The present invention dispenses with the release magnet and transfers the function of effecting restoration or release to normal, to the step-controlling magnet. This permits of a less expensive construction. It 50 also secures an even wear upon the contacts and terminals besides securing other advantages. The switch is automatically set to a predetermined position to prepare it for 55 another selective operation.

The system, in connection with which I have illustrated the invention, provides a novel method of controlling the test circuit which governs the connection of a switch with the proper terminal. The function of 60 this novel method of control is to secure greater reliability and certainty of action than has been considered possible in systems of this class as heretofore constructed. In the accompanying drawings which form a 65 part of the present specification, I have illustrated one embodiment of my invention, in a uni-planar rotary stepping switch employed in a trunk-selecting, call-distributing 70 telephone system.

Figure 1 is a plan view of a switch;

Fig. 2 is a front elevation of the same;

Fig. 3 is a horizontal section taken on the line 3, 3, of Fig. 2; and

Fig. 4 is a circuit diagram of a system 75 employing the switch shown in Figs. 1, 2 and 3.

The switch shown in Figs. 1, 2 and 3 comprises the frame plates 1 and 2, which are provided with suitable bearings 3 and 4, respectively, for mounting a central spindle or shaft 5 which bears the wipers 6, 7, 8 and 9. These wipers are insulated from the shaft 5 and from each other in order to maintain separate independent circuits. 80 The frame plates 1 and 2 have clamped between them by means of the bolt 10, a plurality of semi-circular rows of contacts corresponding in number to the wipers 6, 7, 8 and 9. These contacts 11 are arranged in 85 vertical rows which rows are grouped in the arc of a circle, as is well understood in the art. The contacts 11 are suitably insulated from each other and from the frame of the switch. The upper end of the spindle or shaft 5 bears a ratchet wheel 15 having a suitable number of teeth to provide a stepping tooth for each position of the group 90 of wipers. The ratchet wheel 15 is advanced by means of the stepping magnet 16 which 95 has a suitable stepping pawl 17 held normally out of contact with the teeth of the ratchet wheel 15 by means of the spring 18 and the pin 19. A holding pawl 20, controlled by a suitable spring 21 is provided to hold the ratchet wheel 15 in such position 100 that the wiper group will remain in contact with the desired terminals. The pawl 20 is provided with an extending tail 22 which 105 normally lies in front of the end of the 110

longer spring 23. The spring 23 is provided with a shoulder 24 which is adapted to catch the tail 22 of the pawl 20 when the ratchet wheel 15 has been stepped to the outermost 5 or tripping position. The tail 22 of the pawl 20 normally rests upon the spring 23 and holds the longer springs 23 in contact with the back spring 25. Thus under normal stepping conditions the springs 23 and 10 25 are held in contact. The shaft 5 is secured to the inner end of the spiral springs 26, shown in dotted line in Fig. 1, which springs tend to move the shaft and the attached wiper group back to zero position. 15 A pair of off-normal springs 27 and 28 are mounted on a block of insulation 29 on the top plate 1 in such position that the off-normal pin 30 may engage the longer spring 27 to hold the springs 27 and 28 in open circuit 20 position when the wiper group is at zero. The longer spring 23 is provided with a projection 32 which is adapted to be engaged by an arm of insulating material 33 when the ratchet wheel 15 is returned to the zero 25 position. The ratchet wheel 15 is provided with a suitable number of teeth corresponding to the steps of the switch so that when the wiper group is in contact with the last terminal group and an additional step of the 30 step-controlling magnet 16 is caused the large releasing projection or tooth 34 throws the pawl 20 outward far enough for the tail 22 to drop back of the projection 24 on the springs 23 and thus be held out of operative 35 position. The spring 26 then returns the shaft 5 and the wiper group to zero. Just before the shaft returns completely to the zero position the arm 33 engages the projection 32 on the longer spring 23, forcing the 40 spring outward and thereby releasing the tail 22 of the pawl 20 and causing the pawl to be cast into the teeth of the ratchet 15.

Fig. 4 illustrates a call-distributing telephone system employing the switch above 45 described. Each subscriber's line is provided at central with a trunk selecting switch of the above type. When the subscriber at the station A, which is assumed to be the calling subscriber, closes the circuit 50 of the line wires 40 and 41, by bridging the telephone instrument thereacross, a circuit is closed for the line relay 42 over the following path:—

From the common battery B through the 55 line relay 42, back armature contact 43 of the cut-off relay 44, over the line wire 40 through the instrument bridge at the substation A, line wire 41 through back armature contact 45 to ground at 46. The line 60 relay 42 pulls up the two armatures 46 and 47 against the front contacts, the first contact closing a ground for testing purposes when the switch has stepped from the normal position, as will be described later.

65 The other armature 47 closes the circuit

for the stepping magnet 16. The circuit of the stepping magnet may be traced as follows:—

From battery B through the interrupter 48 through the winding of the magnet 16, 70 armature 47 and front contacts thereof, wire 49 and to ground through the back contact of the cut-off relay armature 50. The stepping magnet is alternately energized and de-energized thereby stepping the wipers 6, 7, 75 8 and 9 from the zero position forward in a search for an idle trunk circuit. Assume that the contact group 51, 52, 53 and 54 is that of the first idle trunk. The wiper group will be stepped to this contact group and 80 when the wiper 8 arrives upon the contact 53 the line cut-off relay 44, which serves also as a test relay, is energized over the following circuit:

From battery B through the winding 56 85 of the relay 55 through the wire 58, back armature contact 59, through the back armature contact 60 of the slow release relay 61, over the private wire 62 of the particular trunk T, which has been selected, through the wiper 8, third wire 63, through the windings 64 and 65 of the cut-off relay 44 in series, to ground by way of the armature contact 46, or by way of the wire 66 and wiper 9 to ground. It will be observed that the wiper 9 95 may be replaced by suitable off-normal contacts, as its function is merely to supply a suitable ground for energizing the cut-off relay 44 when the line of a subscriber A is connected to by means of suitable plug and 100 jack connection, under the condition that this line is the called line.

When the above traced circuit of the relays 44 and 55 is closed, both of the relays are energized. The relay 44 attracts its armature 50 removing ground from the terminals of the stepping magnet 16, thereby stopping further movement of the switch and at the same time closing the armature 50 against the front contact shunting out the 110 winding 64 of the relay 44, leaving only the winding 65 in circuit. The winding 65 of the relay 44 has ample power to hold the armature in attracted position. As the armatures 43 and 45 are attracted, the line wires 115 40 and 41 are connected through the extensions 67 and 68 with the strands 69 and 70 of the link circuit P.

At the same time that the relay 44 is energized the relay 55 attracts its armatures 120 59 and 71. The armature 71 closes the circuit of the signal lamp 72 which serves at this time as a call lamp, indicating to the operator that the trunk T has been selected by the automatic switch of the calling party. 125 The other armature 59 of the relay 55 is attracted to open the shunt about the winding 57. It will be seen that the two relays 44 and 55, which are included in the test circuit, co-operate to increase the margin of 130

operation of the test circuit. The cut-off relay 44 is employed as a testing relay, operating upon a margin of potential. If the contact 53 had been selected by and connected to a wiper of one selecting switch, the potential of the contact should have been so much lowered or modified by the ground connection of the wiper through the testing relay, which selected the particular wiper, 5 that a second switch in testing the contacts would not find sufficient potential to energize its cut-off relays and thus be stopped upon the same contact. By causing the two relays 44 and 55 to coöperate to cut out a part of 10 the winding of one and to cut in a part of the winding of the other, I am able to shift the gradient of potential, with respect to the contact 53, to such an extent that the margin between a busy contact and an idle 15 contact is very large. At the same time the current flow in the relay 44 of the busy line is not larger or substantially larger than when the relay is first energized, but is ample to hold the armatures in attracted position. 20 For instance, assume that the windings 64 and 56 are of 200 ohms each and that the windings 65 and 57 are of 300 ohms each. The total resistance in the circuit at the time 25 that the relays are energized is 700 ohms. 30 The contact 53 is at 100% battery potential before the wiper 8 comes upon it. As soon as the wiper rests upon the contact 53 and before the armatures are shifted, the potential of the contact 53 is about 71% of full 35 battery voltage. The relays are so designed and the voltage so adapted that this voltage is assumed to be necessary for the operation of the windings 64 and 65 in series. When the armatures 50 and 59 are shifted, the contact 40 53 is reduced to a potential of about 29% of full battery voltage which would be insufficient to energize the windings 64 and 65 of another relay.

I do not wish to be limited to these particular values or proportions of resistance and potential.

It can be seen that the arrangement secures greater certainty of operation than any known previous marginal testing circuit. 50 The relay 44 is provided with sufficient ampere turns when it first operates to insure quick operation and prompt stopping of the switch upon the contact selected. After the armatures are attracted a smaller number 55 of ampere turns are required to hold the armatures up. If the relay 55 should be a bit slow in operating, the raising of the armature contact 50 will accelerate and insure the operation of relay 55 by lowering the 60 resistance of the circuit and thus increasing the flow of current until the armature 59 is attracted to break the shunt about the winding 57. As the wipers 6, 7, 8 and 9 are stepped away from zero or normal position, 65 the off-normal contacts 27 and 28 are closed.

The contacts 23 and 25 are held closed by the tail 22 of the pawl 20 and are not opened until the tooth 34 engages the pawl 20 to throw the tail 22 back of the shoulder 24. Assuming that the switch has come to rest 70 upon the contacts 51, 52, 53 and 54, the supervisory relays 73 and 74 are energized by being included in series with the line circuit of the calling subscriber A.

The operator perceiving the signal given 75 by the lamp 72 connects her telephone set 75 to the corresponding link circuit and inquires of the calling party the number of the desired subscriber's line with which connection is to be made. Assume that the line 80 of the party B is desired. The operator inserts the plug 76 into one of the jacks 77 of the desired line and projects ringing current over the called line. When the plug 76 is inserted in the jack, the sleeve of the 85 plug makes contact with the thimble of the jack closing a circuit for the cut-off relay 44'. The energizing circuit of the cut-off relay may be traced from battery B through the sleeve supervisory relay 78 over the 90 sleeve side of the link circuit over the third wire 80 through the windings 64' and 65' in series to ground at the wiper 9'. The cut-off relay 44' attracts its armatures shunting out the winding 64' and leaving the 95 winding 65' in series with the ground armature 50'. It is apparent that the thimble of the jack 77 would test busy if the line of a subscriber B were employed as a calling or as a called line. The sleeve supervisory relay 100 78 attracts its armature 81 thereby closing a circuit for the slow release relay 61 which substitutes itself for the relay 55. When the armature contact 81 is closed the relay 61 is energized over the following circuit:

Battery B, relay 61, armature contact 81, private wire 62, third wire 63, through the winding 65 of the relay 44 to ground by way of the armature contact 50. Energization 110 of the relay 61 opens the armature contact 60 thereby deenergizing the relay 55. This causes the armature 71 to drop back and efface the calling signal 72. The armature 82 of the relay 61 is attracted closing a circuit for the supervisory lamp signal 83 in series with the back armature contact 84 of the tip supervisory relay 85.

When the called party answers, the tip supervisory relay 85 is energized and the 120 lamp 83 is extinguished. When the conversation is finished the parties place their receivers upon the switch hooks thereby breaking the energizing circuit of the respective tip supervisory relays. As the 125 sleeve supervisory relay 78 remains energized, due to the circuit through the third wire 80, the lamp signal 83 will again be energized by dropping back of the armature contact 84 of the tip supervisory relay 85. 130

This lights the supervisory lamp 83 indicating disconnection to the operator. When the plug 76 is withdrawn, the sleeve supervisory relay is deenergized breaking the circuit of the slow release relay 61. The relay 61 is made a slow release relay as by means of a copper jacket or the equivalent to cause it to retain its armature in attracted position for a short period of time after the energizing circuit is broken. This slow release is desirable to permit the relay 44 to be deenergized to release its armature. That is to say since the armature contacts 81 and 60 are both open, the relay 44 becomes deenergized releasing its armatures 45, 43 and 50. The armature 50 drops back against the back contact closing the stepping circuit for the magnet 16 through the off-normal contacts 27 and 28 which are closed due to the off-normal position of the switch, through the contacts 25 and 23 which are held closed by the tail 22 of the pawl 20 through the back armature contact 47, winding of the stepping magnet 16, through the interrupter 48 and to battery B. The switch is then stepped forward to release. The above stepping circuit remains closed until the pawl 20 is tripped out of the ratchet by the tooth 34. The tail of the pawl drops off of the shoulder 24 and is held out of contact with the ratchet. The spring 26 immediately moves the shaft back to the zero position. As the switch approaches zero, the arm 33 engages the pin or stud 32 and forces the long spring 23 outward to release the tail of the pawl 20 and to close the spring 23 against the back contact 25. At the same time the pin 30 on the ratchet wheel 15 moves the longer spring 27 away from the back contact 28 breaking the circuit of the stepping magnet at this point.

The switch is then in condition to be actuated to make another selection when the same is desired.

It will also be apparent that if all the trunks are busy at the time a switch is operating to select, the wipers will continue their advance over all the contacts 51, 52 and 53 until they reach the end of the row whereupon the release mechanism comes into play and the wipers restore and immediately start their advance again, until an idle trunk T is selected. It will also be seen that a switch will thus reciprocate in such release and advance operations until an idle trunk is reached.

The system that I have above described is characterized by simplicity and certainty of operation. The cut-off relay is employed as a testing relay and due to the arrangement of coöperation between the relays 44 and 55 the margin of potential is so greatly increased as to insure certainty of operation under all normal conditions.

I wish it to be understood that instead of

employing a horse-shoe magnet for the stepping magnet 16, as I have shown in Figs. 1 and 2, I intend also to employ a single winding for the magnet 16 in which case the bracket 86 and the armature bar 87 are made of magnetic material to form substantially a complete magnetic circuit. The advantage of this form of stepping magnet is that the overall thickness of the switch may be materially reduced when space is a valuable consideration. In addition it will be noted that only a single air gap will be necessary in the latter form as compared with two air gaps when a horse-shoe form of magnet is employed.

I find that the windings 64 and 57 may be replaced with dead resistance which may be disposed upon the cores of the relays or may be external resistance. That is to say the windings 65 and 57 of either or both relays may be supplanted in whole or in part with resistance disposed either on the cores or external to the relays.

What I claim is:

1. In a switch of the class described, a shaft, a plurality of wipers controlled by movement of said shaft, a plurality of stationary contacts adapted to be engaged by said wipers, a ratchet wheel secured to said shaft, a stepping magnet having a stepping pawl for engaging said ratchet, a holding pawl for engaging said ratchet, said ratchet having a projecting tooth or arm for moving said retaining pawl away from said ratchet, a spring for engaging said pawl to hold the same away from the ratchet, and means operated by return of the shaft to normal to release said pawl from said spring.

2. In combination, a plurality of stationary contacts, a plurality of movable wipers adapted to make contact with said stationary contacts, a shaft for controlling said wipers, a ratchet for the shaft, a stepping magnet for operating said ratchet, a pawl normally engaging said ratchet, said ratchet having means for throwing said pawl outward, means for holding said pawl outward, said means controlling the circuit of the stepping magnet.

3. In combination, a bank of contacts, a wiper for said contacts movable in a single plane only, a controlling ratchet member fixedly secured to said wiper, driving means for moving said member from zero through a predetermined range of movement, a pawl to hold the ratchet member in intermediate positions corresponding to said contacts, means actuated by the driving means for preparing the driving means for subsequently restoring the wiper, and means conditioned by movement of said ratchet member to the limit of its range to restore said ratchet and wiper to zero.

4. In combination a bank of contacts, a

wiper adapted to be moved over said contacts, a controlling ratchet member for said wiper, said member being movable from zero through a predetermined range of movement, a stepping magnet, a circuit for said magnet, a pair of contacts in said circuit, said contacts being opened by movement of said ratchet to the limit of movement, means for restoring said ratchet member to zero and means for holding the contacts open until said ratchet returns to zero.

5. In combination a bank of contacts, a wiper adapted to be moved over said contacts, a controlling ratchet member for said wiper, said member being movable from zero through a predetermined range of movement, a stepping magnet for said ratchet, a circuit for said magnet, a pair of contacts in said circuit, a pawl to hold the ratchet member in any intermediate position, means conditioned by movement of said ratchet member to the limit of its range to disengage said pawl from the ratchet member and to hold said contacts open until said ratchet returns to normal.

6. In combination a bank of contacts, a wiper adapted to be moved over said contacts, a controlling ratchet member for said wiper, said member being movable from zero through a predetermined range of movement, a stepping magnet for said ratchet, a circuit for said magnet, a pair of contacts in said circuit, a pawl to hold the ratchet member in any intermediate position, means conditioned by movement of said ratchet member to limit of its range of movement to disengage said pawl from said ratchet and to open said contacts, said pawl and said contacts being interlocked until 35 said ratchet member returns to zero, and means controlled by said ratchet member to throw the pawl into engagement with the ratchet and to close said contacts.

7. In combination, a bank of contacts, arranged in the arc of a semi-circle, a wiper adapted to be moved over said contacts, a ratchet member, a shaft connecting said ratchet member and said wiper, said ratchet member being movable from zero through 45 a predetermined range of movement, a restoring spring connected to said shaft, a pawl adapted to hold the ratchet member in any intermediate position, said ratchet member having means for disengaging said pawl when the ratchet is at the limit of its movement, a stepping magnet, a circuit for said magnet, a controlling spring in said circuit, said spring having means interlocking with said pawl for holding the pawl 50 away from the ratchet until said ratchet returns to zero.

8. In a switch of the class described, a ratchet member, a stepping magnet, a controlling spring for said magnet, said spring having a shoulder, said pawl having a tail,

said shoulder and said tail being adapted to interlock, said ratchet member being adapted to be moved from zero to a predetermined position, and a spring for returning said ratchet to zero position, said ratchet having means adapted when the ratchet is moved to the limit of its range of movement to place the pawl under the control of said spring and having further means adapted when said ratchet is returned to zero to place said spring under the control of said pawl.

9. In a switch a ratchet member, a stepping magnet for said ratchet member, a pawl, a spring for controlling the circuit of said stepping magnet, said ratchet having means adapted to throw said pawl out of action at one limit of the range of movement and having further means for causing said pawl to engage said ratchet at the other end of the range of movement, said spring being controlled by said pawl.

10. In combination an automatic switch, a line controlling the switch, said switch having a private wiper and a plurality of private contacts, stepping means for causing said switch to move over said contacts, a testing circuit adapted to be closed by said wiper and one of said contacts, a cut-off relay controlling said stepping means, and controlling the normal connections of the line, said relay being connected in series relation with said wiper, a controlling relay connected to one of said private contacts, one of said relays comprising an armature adapted when attracted to cut out a portion of its winding and establish a local locking circuit to eliminate a predetermined amount of resistance from said testing circuit, and the other of said relays having an armature adapted when energized to include a predetermined amount of resistance in said testing circuit.

11. In combination an automatic selecting switch, a line controlling the switch, said switch having a private wiper and a plurality of private contacts adapted to be engaged by said wiper, a testing circuit adapted to be closed by said wiper and one of said contacts, means for causing said switch to move over said contacts, said means comprising a step-controlling magnet, a cut-off relay controlling said step-controlling magnet and controlling the normal connections of said line, said relay being connected to 115 said wiper, and a controlling relay connected to one of said private contacts, said relays cooperating to shift the gradient of potential of said connected contacts to increase the margin of operation by establishing a locking circuit through a portion of the winding of one relay and cutting in an additional winding on the other.

12. In combination, a calling line, a plurality of line extensions, means to close con-

- 6
- nection between said calling line and an idle one of said line extensions, said means comprising contact sets connected to said line extensions and a coöperating wiper set, a 5 stepping magnet, a ratchet member having a predetermined range of movement and fixedly attached to the wiper set, a pawl for holding said ratchet member at intermediate positions corresponding to said contact sets, 10 an energizing circuit for the stepping magnet having a contact closed on initial actuation of said magnet for subsequently effecting a restoring advance of the switch, means for throwing said pawl out of action at one 15 end of the range of movement, a spring for restoring said ratchet member and means for throwing said pawl into action at the other limit of the range of movement.
13. In a switch, a single row of stationary contacts, a wiper movable along in engagement with said contacts, a ratchet member having motion in a single plane, a pawl for said ratchet, a single stepping magnet, an energizing circuit for the stepping magnet 25 having a contact closed on initial actuation of said magnet subsequently effecting a restoring advance of the switch, and means controlled by said stepping magnet for disengaging said pawl from said ratchet while the ratchet returns to zero.
14. In combination, a circular contact bank, a rotary wiper, a ratchet for driving the wiper, a stepping magnet having a pawl for driving the ratchet, a holding pawl for 30 the ratchet, a projecting member connected to the ratchet for disengaging the holding pawl, a catch for blocking the holding pawl away from the ratchet and means connected to the ratchet for disengaging the blocking means when the wiper is restored to zero.
15. In combination, a line terminating in an automatic switch, a plurality of link circuit terminals banked in said switch, a line 35 cut-off relay individual to the line, a relay individual to the link circuit selected, said switch having a wiper adapted to put the line cut-off relay in series with the link circuit relay, means including a driving circuit for advancing the wiper, said circuit including normally closed contacts of the line cut-off relay, and a calling signal controlled by the link circuit relay.
16. In combination, a line terminating in an automatic switch, a plurality of link circuit terminals banked in said switch, a line 45 cut-off relay individual to the line, a relay individual to the link circuit selected, said switch having a wiper adapted to put the line cut-off relay in series with the link circuit relay, and means for advancing the wiper, said means being controlled by the line cut-off relay, means controlled by 50 said relays for changing the potential of the link circuit terminals to render them non-selectable by establishing a locking circuit 65 through a portion of the winding of the line cut off relay and cutting in an additional winding on the link circuit relay.
17. In combination, a line terminating in an automatic switch, a plurality of link circuit terminals banked in said switch, a line 70 cut-off relay individual to the line, a relay individual to the link circuit selected, said switch having a wiper adapted to put the line cut-off relay in series with the link circuit relay, and means for advancing the wiper, said means being controlled by the line cut-off relay for cutting resistance out of the circuit and means controlled by the link circuit relay for cutting resistance into the circuit for changing the potential on the selected link terminals to render them non-selectable.
18. In combination, calling lines, automatic switches individual to the calling lines, link circuits having multiple contacts in the contact banks of the switches, each switch comprising a group of contacts all arranged in a single plane and a wiper having a limited range of movement and adapted to be moved successively in engagement with the contacts, a stepping magnet, means controlled over the calling line to cause the stepping magnet to advance the wiper, means for holding the wiper in engagement with the contacts of a link circuit, means actuated by the stepping magnet for controlling subsequent release actuation of the stepping magnet, and means rendered operative by the stepping magnet when the wiper is at the limit of its range of movement for disabling the holding means and permitting the wiper to return to zero.
19. In a switch, a bank of stationary contacts arranged in a single plane, a wiper having a limited range of movement, said wiper being normally in zero position, a single magnet controlling the advance of the wiper step by step, means for opening the magnet circuit at a given point and for causing the wiper to return to zero, said means being rendered active by movement of the wiper to the limit of its range of movement, means for closing the circuit at that point when the wiper returns to zero and means for opening the circuit of the magnet at another point when the wiper returns to zero.
20. In combination, automatic switches, calling lines terminating in said automatic switches, link circuits terminating in multiple bank contacts in said switches, the bank contacts being arranged in a single plane, the wipers having a limited range of movement, a single magnet in each switch controlling the advance and restoration of said wipers, and a testing magnet for each calling line, said

testing magnet serving as a line cut-off relay and serving as a cut-off relay for the controlling magnet of the switch.

21. In combination, a line terminating in the wipers of an automatic switch, said switch comprising a group of contacts all arranged in the arc of a circle and wipers having a normal position, a single magnet controlling advancing and restoring movement of the wipers of the switch each time it is used, and a single relay serving as a line cut-off for the line and as a test relay for the switch.

22. In combination, a line terminating in a switch having bank contacts, link circuits connected to said contacts, a relay individual to the line serving as a cut-off relay for the line and a test relay for the switch, a signal relay individual to the link circuit, both of said relays being connected in series by the switch and coöperating to change the potential of the corresponding bank contacts, a slow release relay individual to the link circuit, and a sleeve relay for the remote end of the link circuit adapted to substitute the slow relay instead of the signal relay in the circuit of the cut-off relay.

23. In a telephone system, a switch, a link circuit terminating in the switch, a signal relay individual to the link circuit and connected in the third wire of the link circuit, a retarded release relay adapted to be substituted for the signal relay in said third wire and means for substituting said release relay for the signal relay.

24. In combination, a telephone line, an automatic switch individual thereto, said switch having a contact bank, and contacts all lying in a single plane, a movable wiper for engaging said contacts, said wiper having a limited range of movement, talking wires terminating in said contacts, means to advance the wiper step by step into selective engagement with one of said contacts and means for thereafter automatically restoring the wiper to zero by automatically advancing the wiper to the limit of its range of movement.

25. In combination, a telephone line, an automatic switch individual thereto, said switch having a contact bank, and contacts all lying in a single plane, a movable wiper adapted to be advanced in engagement with said contacts, said wiper having a limited range of movement, and talking wires terminating in said contacts, said switch having a single stepping magnet for controlling the stepping of the switch to a selected contact and for causing restoration of the switch, and automatic means for operating said magnet for causing a restoring advance to effect restoration of the switch.

26. In combination, a switch having bank contacts all arranged in a single plane in the

arc of a circle, and a wiper for engaging said contacts, a calling line terminating in the wiper of said switch, a plurality of link circuits terminating in the bank contacts, a single stepping magnet controlled over the line for automatically connecting the wiper to the contact of an idle link circuit, means for holding the wiper in engagement with a so connected contact and means controlled by the stepping magnet for disengaging the holding means.

27. In a telephone system, a telephone line, an automatic switch having wipers for said line, bank contact sets for said switch, telephone circuits connected to said contact sets, driving means for moving said wipers in a single plane only to select a contact set of said switch, a relay operable over the telephone line to cause such operation of the switch, a pawl for holding the wipers in their selected position, means responsive to an interruption of the telephone line, to cause said driving means to continue the advance of the wipers to a predetermined position, and means for thereupon disengaging said holding pawl whereby said wipers are restored to normal.

28. In a telephone system, a telephone line, an automatic switch having wipers for said line, bank contact sets for said switch, telephone circuits connected to said contact sets, driving means for moving said wipers in a single plane only to select a contact set of said switch, a relay operable over the metallic circuit of the telephone line to cause such operation of the switch, a pawl for holding the wipers in their selected position, means responsive to an interruption of the telephone line, to cause said driving means to continue the advance of the wipers to a predetermined position, and means for thereupon disengaging said holding pawl whereby said wipers are restored to normal.

29. In a telephone system, telephone lines, automatic switches each having a wiper set for one of said lines, bank contact sets for said switches, telephone circuits multiply connected to said contact sets, driving means for each of said switches for moving the wipers in a single plane only to select one of said contact sets, a relay for each telephone line operable thereover to cause such operation of the corresponding switch, a pawl for each switch for holding the wipers in their selected position, means responsive to an interruption of the telephone line, to cause said driving means to continue the advance of the wipers of an operated switch to a predetermined position, and means for thereupon disengaging said holding pawl whereby said wipers are restored to normal.

30. In a telephone system, telephone lines, automatic switches each having a wiper set for one of said lines, bank contact sets for

said switches, telephone circuits multiply connected to said contact sets, driving means for each of said switches for moving the wipers in a single plane only to select one 5 of said contact sets, a relay for each telephone line operable over the metallic circuit thereof to cause such operation of the corresponding switch, a pawl for each switch for holding the wipers in their selected position, means responsive to an interruption 10 of the telephone line, to cause said driving means to continue the advance of the wipers of an operated switch to a predetermined position, and means for thereupon disengaging 15 said holding pawl whereby said wipers are restored to normal.

31. In a telephone system, telephone lines, automatic switches each having a wiper set for one of said lines, bank contact sets for 20 said switches, telephone circuits multiply connected to said contact sets, each switch having its contact sets all arranged in a single plane and its wiper set having a limited range of movement and adapted to be moved 25 successively in engagement with the contacts, a stepping magnet for each switch, means controlled over a calling line to cause the stepping magnet of the corresponding switch to advance the wiper set, means for holding 30 the wiper set in engagement with the contacts of a telephone circuit, and means including a circuit operated upon the initial actuation of the switch for subsequently causing said magnet to advance an operated 35 wiper set to the limit of its range of movement for disabling the holding means and permitting the wiper set to return to zero.

32. In a telephone system, telephone lines, automatic switches each having a wiper set 40 for one of said lines, bank contact sets for said switches, telephone circuits multiply connected to said contact sets, each switch having its contact sets all arranged in a single plane and its wiper set having a limited 45 range of movement and adapted to be moved successively in engagement with the contacts, a stepping magnet for each switch, means controlled over the metallic circuit of a calling 50 line to cause the stepping magnet of the corresponding switch to advance the wiper set, means for holding the wiper set in engagement with the contacts of a telephone circuit, and means including a circuit operated upon the initial actuation of the 55 switch for subsequently causing said magnet to advance an operated wiper set to the limit of its range of movement for disabling the holding means and permitting the wiper set to return to zero.

60 33. In a telephone system, a telephone line, an automatic switch having wipers for said line, bank contact sets for said switch, operators' link circuits connected to said contact sets, driving means for moving said 65 wipers in a single plane only to select a con-

tact set of an idle link circuit, a relay operable over the circuit of the telephone line to cause such operation of the switch, a pawl for holding the wipers in their selected position, means controlled by the operator to 70 cause said driving means to continue the advance of the wipers to a predetermined position, and means for thereupon disengaging said holding pawl whereby said wipers are restored to normal.

75 34. In a telephone system, telephone lines, automatic switches each having a wiper set for one of said lines, bank contact sets for said switches, operators' link circuits multiply connected to said contact sets, driving 80 means for each of said switches for moving the wipers in a single plane only to select a contact set on an idle link circuit, a relay for each telephone line operable over the circuit thereof to cause such operation of the corresponding switch, a pawl for each switch for holding the wipers in their selected position, means controlled by the operator to cause said driving means to continue the advance of the wiper set of an operated switch 85 to a predetermined position, and means for thereupon disengaging said holding pawl whereby said wipers are restored to normal.

90 35. A selector switch comprising contacts and coöperating wipers, a line relay, a cut-off relay, a driving and release magnet, a driving circuit for said magnet controlled through normally open contacts on the line relay, and a release driving circuit for said magnet including normally closed contacts 100 on the line relay and normally open off-normal contacts.

95 36. A selector switch comprising contacts and coöperating wipers, a line relay, a cut-off and test relay, a driving and release magnet, a driving circuit for said magnet controlled through normally open contacts on the line relay, a release driving circuit for said magnet including normally closed contacts on the line relay and normally open 110 off-normal contacts, and contacts on the cut-off and test relay for interrupting the driving circuit for said magnet.

115 37. A selector switch comprising contacts and coöperating wipers, a line relay, a cut-off and test relay, a driving and release magnet, a driving circuit for said magnet controlled through normally open contacts on the line relay and normally closed contacts on the cutoff and test relay, and a release driving circuit for said magnet including normally closed contacts on the line relay and normally open off-normal contacts and normally closed contacts on the cutoff and test relay.

120 38. A selector switch comprising contacts and coöperating wipers, a line relay, a cut-off and test relay, a driving and release magnet, a driving circuit for said magnet controlled through normally open contacts on 130

- the line relay and normally closed contacts on the cutoff and test relay, and a release driving circuit for said magnet including normally closed contacts on the line relay and normally open off-normal contacts and normally closed contacts on the cutoff and test relay, normally closed contacts opened and held open upon release of the switch and included in the release circuit of the magnet.
39. In a telephone system, an automatic switch, lines terminating in bank contacts of said switch, means for advancing the wipers of said switch over the bank contacts, means for stopping the wipers upon a set of said contacts if idle, a ratchet included in the advancing means and a holding pawl therefor, means operative when the wipers are advanced to a predetermined position for disengaging said pawl from the ratchet to allow the wipers to restore whereupon they are again advanced over the bank contacts, and a restoring circuit for subsequently operating the advancing means having a contact closed upon the initial movement of the switch.
40. In a telephone system, a telephone line, an automatic switch, lines terminating in bank contacts of said switch, means controlled over the line when calling for advancing the wipers of said switch over the bank contacts, means for stopping the wipers upon engagement with a set of idle contacts, a ratchet included in said driving means and a holding pawl therefor, mechanical means operative when the wipers are advanced over all of the contacts if busy for disengaging said pawl from the ratchet to allow the wipers to restore whereupon they are again advanced under control of the line to seek a set of idle contacts, and a restoring circuit for subsequently operating the advancing means having a contact closed upon the initial movement of the switch.
41. In a telephone system, an automatic switch, a group of lines terminating in contacts of said switch, means for driving said automatic switch over the contacts of said group, means for causing said switch to stop upon a set of electrically distinguished contacts, a restoring spring for said switch, means operated when said automatic switch reaches a pre-determined position to allow said spring to restore said switch to its normal position whereupon it is again driven over the contacts of said group, and means actuated by said driving means for preparing the driving means for effecting subsequent restoring advance of the switch.
42. In a telephone system, an automatic switch, a group of lines terminating in contacts of said switch, means for driving said automatic switch over the contacts of said group, means for causing said switch to stop upon a set of electrically distinguished contacts, a ratchet, a pawl normally in engagement with said ratchet for holding said switch in its actuated position, mechanical means operated when said automatic switch reaches a predetermined position for withdrawing said pawl from said ratchet to allow said switch to restore to its normal position whereupon it is again driven over the contacts of said group, and means actuated by said driving means for preparing the driving means for effecting subsequent restoring advance of the switch.
43. In a telephone system, an automatic switch, a group of lines terminating in a row of contacts of said switch, means for driving said automatic switch over the entire row of said terminals, a ratchet, a pawl normally in engagement with said ratchet for preventing the restoration of said switch, means for causing said switch to stop upon a set of electrically distinguished contacts, mechanical means operated when said automatic switch reaches the end of said row to withdraw said pawl from said ratchet to allow said switch to return to the beginning of said row, whereupon said switch is again driven over said row, and means actuated by said driving means for preparing the driving means for effecting subsequent restoring advance of the switch.
44. In a telephone system, a telephone line, an automatic switch, lines terminating in bank contacts of said switch, means controlled over the line when calling for advancing the wipers of said switch over the bank contacts, means for stopping the wipers upon engagement with a set of idle contacts, a ratchet included in said driving means and a holding pawl therefor, mechanical means operative when the wipers are advanced over all of the contacts if busy for disengaging said pawl from the ratchet to allow the wipers to restore whereupon they are again advanced under control of the line to seek a set of idle contacts, and circuit connections thereafter responsive to an interruption of the line for causing the advancing means to act upon the wipers to again move them over the contacts to bring about a restoration thereof.
- In witness whereof, I hereunto subscribe my name this 17th day of April A.D. 1916.

HARRY G. WEBSTER.
